ATTORNEY.

UNITED STATES PATENT OFFICE.

HENRY THOMAS BROOKER, OF SOUTHEND-ON-SEA, ENGLAND.

APPARATUS FOR PLAYING RACE GAMES.

Application filed December 21, 1922. Serial No. 608,301.

To all whom it may concern:

Be it known that I, HENRY THOMAS BROOKER, a subject of the King of Great Britain, residing at Southend-on-Sea, Essex, England, have invented certain new and useful Improvements in Apparatus for Playing Race Games, of which the following is a specification.

This invention relates to apparatus for playing a parlour, table or the like game or mechanical toy.

The manufacture of the apparatus under the present invention is notably one not calling for highly skilled labour as the major components of the apparatus are adapted to be made from stampings and the assemblage of the various components does not call for highly skilled assemblers.

The invention constitutes a new or improved apparatus of the mechanical race game type.

Under a feature of the present invention there is provided apparatus for playing a race or the like game wherein each propelled unit of an abreast series of units is advanced along a track towards a target by a series of intermittent thrusts imparted by an actuating device through the mediation of a freely moving propelling unit, this propelling unit co-operating with the actuating device so that the series of intermittent thrusts are variable both in magnitude and period.

Under a further feature of the present invention there is provided means common to all of the propelling units for actuating the propelling units to impart to the model figures a series of intermittent thrusts.

Thus under the present invention an apparatus comprises a board or table having guide-ways or tracks for the reception of propelled units, as for example, model figures such as horses or motor-cars. At one end of each of the guide-ways or tracks there is provided means for actuating a propelling unit, this propelling unit imparting to the model figure in the guide-way or track a series of intermittent thrusts. Upon receiving the thrusts each model figure is propelled along its particular guide-way towards a target or indicator arranged at or adjacent to the end of the guide-way remote from that having the actuating means for the propelling unit.

The target may be so arranged, as by the provision of an engaging piece, as to be

moved from its normal position to an indicating position when the model figure comes into contact with the engaging piece, the target or indicator when raised thus signifying that the model figure had reached the allotted distance of travel.

The propelling units for all the guide-ways may be under the action of a single actuating device, which device may be so arranged as to receive motion at irregular intervals from a tappet device as for example a rotating disc or wheel having a contact piece for engaging an appropriate part of the actuating device.

The actuating device may comprise a rocker bar one arm of the bar operating on the aforementioned propelling units when the other end of the bar is pushed by the tappet device.

In the accompanying drawings there is shown by way of example an apparatus made according to the present invention:

Fig. 1 is a plan view, Fig. 2 a sectional side view on the line A—A (Fig. 1), while Figs. 3 and 4 are detail views hereinafter referred to:

Referring to the drawings there is provided a base board 1 having a series of tracks 2 thereon. Each track is so arranged as to receive and retain therein a model figure 3 adapted to move freely therewith.

A rocker bar 4 is fulcrumed on the base board 1 so that one arm thereof extends across the tracks at or near to the bottom ends thereof.

Interposed between the model figures 3 and the rocker bar arm are propelling units 5 in the form of steel balls.

The arm of the rocker bar 4 may have a resilient pad 4^a at the part contacting with the propelling units 5.

The other arm of the rocker bar 4 is under the influence of a tappet device 5^a carried by a suitably mounted rotating disc or wheel 6, movement being imparted thereto by a winding movement and a sudden or quick release.

At or near to the top end of each track 2 is arranged a pivoted target or indicator 7 the normal positions of these targets or indicators being in substantial parallelism with the track surface as shewn in Fig. 1.

Co-operating means having one element 9 on the model figure 3 and the other element 8 on the target or indicator 7 are provided whereby upon a model figure hav-

ing been propelled to a certain position along the track the co-operating means become effective to raise the target or indicator to stand for example at right angles 5 to the track surface. Upon disengagement of the two elements of the co-operating means the target or indicator returns to its normal position.

A general slope is given to the tracks 10 from the target ends down to the bottom ends. This may be provided for by supports 10.

For convenience of manufacture the series of targets or indicators 7 may have a common pivot bar or rod 11 carried in suitable 15 bearings. Further the tracks may be formed by a series of spaced strips or laths 12 mounted on studs or spacing strips 13.

Provision is made as by slipper and guide 20 connections between the model figures and the tracks for preventing withdrawal of the model figures in an upward direction.

The rocker bar 4 is moved to contact with the tappet device 5^a when commencing a 25 game. Upon movement of the rocker bar 4 by the tappet device 5^a the propelling units or balls 5 impart a thrust or push to the model figures 3 and move these a certain 30 distance along the tracks 2. Upon cessation of the thrust the propelling units 5 by reason of the general slope of the tracks 2 fall back to the rocker bar 4 and the return 35 action of one or more of these propelling units 5 assists in again bringing the rocker bar under the influence of the tappet device 5^a. The pivotal setting of the rocker bar may be such that this normally returns to contact position with the tappet device.

The continued action of the rocker bar 4 on the propelling units 5 is variable both in the magnitude of the force or thrust imparted and the moment or period of action, as these conditions are determined by the fall or return of the propelling units 5 which fall or return becomes irregular, the return 45 of the series of propelling units 5 being scarcely ever in unison. Thus the advance of any one of the model figures 3 towards the targets 7 is variable in relationship to the remainder of the model figures.

Means may be provided whereby the leverage action on the propelling units may be compensated for so that the maximum thrust imparted to the propelling units will not be governed by the distance of each unit 55 from the fulcrum. For example resilient buffers of varying capacity for softening the impact may be provided on the rocker bar by which a yielding thrust is imparted to the propelling units.

A reciprocating bar may take the place of a rocker bar, in which case suitable linking mechanism will be interposed between this reciprocating bar and the tappet mechanism.

A scoring board and other convenient or desirable fittings or attachments may be provided.

Suitable stops and catches may be provided for the rocker bar whereby its various 70 positions may be controlled. For example a pivoted stop 14 may be provided for retaining the rocker bar in its normal or out of action position.

Various devices may be used for imparting movement to the tappet device. For example an electrical or clockwork driven unit may take the place of the spinning wheel or disc 6.

What I claim is:—

1. Game playing apparatus comprising a board, an abreast series of tracks thereon, the tracks sloping to one end, a corresponding series of units mounted capable of propulsion along the tracks, an actuating device 80 in each track for imparting intermittent thrusts to the unit therein to advance it therealong, the actuating devices being returned by gravity along the sloping tracks after impact, means for intermittently impelling the actuating devices, and indicating means at the finishing end of the tracks adapted to be operated from a normal to an indicating position by a unit as it completes its allotted distance of travel.

2. Game playing apparatus comprising a board, an abreast series of tracks thereon, the tracks sloping to one end, a corresponding series of figures mounted capable of propulsion along the tracks, a freely moving 100 propelling unit in each track for imparting intermittent thrusts to the unit therein to advance it therealong, the propelling units being returned by gravity along the sloping tracks after impact, means common to all 105 the propelling units for intermittently impelling these, and indicating means at the finishing end of the tracks adapted to be operated from a normal to an indicating position by a unit as it completes its allotted distance of travel.

3. Game playing apparatus comprising a board, an abreast series of tracks thereon, the tracks sloping to one end, a corresponding series of units mounted capable of propulsion along the tracks, an actuating device in each track for imparting intermittent thrusts to the unit therein to advance it therealong, the actuating devices being returned by gravity along the sloping tracks after impact, means for intermittently impelling the actuating devices so that the series of intermittent thrusts are variable 115 both in magnitude and period, and indicating means at the finishing end of the tracks adapted to be operated from a normal to an indicating position by a unit as it completes its allotted distance of travel.

4. Game playing apparatus comprising a board, an abreast series of tracks thereon,

the tracks sloping to one end, a corresponding series of units mounted capable of propulsion along the tracks, an actuating device in each track for imparting intermittent thrusts to the unit therein to advance it therealong, the actuating devices being returned by gravity along the sloping tracks after impact, and means for intermittently impelling the actuating devices so that a series of intermittent thrusts are given that are variable both in magnitude and period.

5. Game playing apparatus comprising a board, an abreast series of tracks thereon, the tracks sloping to one end, a corresponding series of units mounted capable of propulsion along the tracks, an actuating device in each track for imparting intermittent thrusts to the unit therein to advance it therealong, the actuating devices being returned by gravity along the sloping tracks after impact, means for intermittently impelling the actuating devices, a tappet device for actuating the impelling means, and indicating means at the finishing end of the tracks adapted to be operated from a normal to an indicating position by a unit as it completes its allotted distance of travel.

6. Game playing apparatus comprising a board, an abreast series of tracks thereon, the tracks sloping to one end, a corresponding series of units mounted capable of propulsion along the tracks, an actuating device in each track for imparting intermittent thrusts to the unit therein to advance it therealong, the actuating devices being returned by gravity along the sloping tracks after impact, a rocker bar for intermittently impelling the actuating devices, a tappet device for actuating the rocker bar, and indicating means at the finishing end of the tracks adapted to be operated from a normal to an indicating position by a unit as it completes its allotted distance of travel.

45 7. Game playing apparatus comprising a board, an abreast series of tracks thereon, the tracks sloping to one end, a corresponding series of units mounted capable of propulsion along the tracks, an actuating device in each track for imparting intermittent thrusts to the unit therein to advance it therealong, the actuating devices being returned by gravity along the sloping tracks after impact, means for intermittently impelling the actuating devices, and a plurality of indicators mounted on a common pivot bar at the finishing end of the tracks, each indicator adapted to be operated from a normal to an indicating position by a unit as it completes its allotted distance of travel.

8. Game playing apparatus comprising a board, an abreast series of tracks thereon, the tracks sloping to one end, a corresponding series of units mounted capable of prop-

pulsion along the tracks, an actuating device in each track for imparting intermittent thrusts to the unit therein to advance it therealong, the actuating devices being returned by gravity along the sloping tracks after impact, a rocker bar for intermittently impelling the actuating devices, means for compensating the leverage action of the rocker bar, and indicating means at the finishing end of the tracks adapted to be operated from a normal to an indicating position by a unit as it completes its allotted distance of travel.

9. Game playing apparatus comprising a board, an abreast series of tracks thereon, the tracks sloping to one end, a corresponding series of figures mounted capable of propulsing along the tracks, a freely moving propelling unit in each track for imparting intermittent thrusts to the unit therein to advance it therealong, the propelling units being returned by gravity along the sloping tracks after impact, and means for intermittently impelling the propelling units so that a series of intermittent thrusts are given that are variable both in magnitude and period.

10. Game playing apparatus comprising a board, an abreast series of tracks thereon, the tracks sloping to one end, a corresponding series of units mounted capable of propulsing along the tracks, a freely moving ball in each track for imparting intermittent thrusts to the unit therein to advance it therealong, the balls being returned by gravity along the sloping tracks after impact, means for intermittently impelling the actuating devices, and indicating means at the finishing end of the tracks adapted to be operated from a normal to an indicating position by a unit as it completes its allotted distance of travel.

11. Game playing apparatus comprising a board, an abreast series of tracks thereon, the tracks sloping to one end, a corresponding series of units mounted capable of propulsing along the tracks, a freely moving ball in each track for imparting intermittent thrusts to the unit therein to advance it therealong, the balls being returned by gravity along the sloping tracks after impact, a rocker bar for intermittently impelling the actuating devices, a tappet device for actuating the rocker bar, and indicating means at the finishing end of the tracks adapted to be operated from a normal to an indicating position by a unit as it completes its allotted distance of travel.

12. Game paying apparatus comprising a board, an abreast series of tracks thereon, the tracks sloping to one end, a corresponding series of units mounted capable of propulsing along the tracks, a freely moving ball in each track for imparting intermittent thrusts to the unit therein to advance

it therealong, the balls being returned by gravity along the sloping tracks after impact, a rocker bar for intermittently impelling the actuating devices, a tappet device 5 for actuating the rocker bar, and a plurality of indicators mounted on a common pivot bar at the finishing end of the tracks, each

indicator adapted to be operated from a normal to an indicating position by a unit as it completes its allotted distance of travel. 10

In testimony whereof, I affix my signature.

HENRY THOMAS BROOKER.
